PRINTER SLOTTER

Thomas S. Fitchett, Glenarm, Md., assignor to
 F. X. Hooper Company, Inc., Glenarm, Md.,
 a corporation of Maryland

Application January 4, 1936, Serial No. 57,508

11 Claims. (Cl. 101—247)

This invention relates to a printing and slotting machine primarily used for making carton blanks from corrugated sheet material. It has been customary to operate such a machine to deliver approximately one hundred sheets per minute and at such slow speeds the machines previously available have been fairly satisfactory.

Increased production has required that machines be developed that will deliver from two hundred to two hundred and fifty sheets per minute and the pile of corrugated board on the feed table sometimes weighs several hundred pounds. These separate sheets or boards are delivered to the printing and slotting rollers of the machine by a reciprocating feed which has to take the sheet from a stationary position and accelerate its speed until it is moving through the machine at a speed of approximately one thousand lineal feet per minute. The constant reversal of this reciprocating feed, calling for between four hundred and five hundred reversals per minute, has previously required a machine of very heavy and expensive construction. The former practice has been to make the presser rollers and impression cylinders hereinafter generally referred to as presser rollers, vertically adjustable. The purpose of this has been to permit the use of the machine on several thicknesses of corrugated board. The use of different thicknesses of corrugated board has now become quite prevalent because of the expense saved in the use of the thinner board for many operations. This vertical adjustment of the presser rollers requires that the lower section of the printer slotter have many vertical cutaway portions therein to accommodate the sliding blocks for the bearings of the shafts carrying these rollers. This vertical cutting up of the lower section of the printer slotter side frames imparted to them a very considerable weakness in view of the constant reciprocating motion applied to the machine by the feed and the intermittent strain applied to the rollers by the passing of successive blanks between the same. This vertical cut construction of the side frames necessitated excessively heavy material in the side frames so that adequate support could be given to the presser rollers.

Such machines have always been driven from one source of power and power has been transmitted from one roller to another through the use of intermediate gears. Usually, with the vertical adjustment, intermediate gears, geared together, were likewise geared to the shafts of

upper and lower rollers. Likewise these intermediate gears were geared to other intermediate gears in order to transmit the power on to the successive printing, scoring and slotting rollers and other lower presser rollers. Such structure involved the use of many gears and on vertical adjustment of the presser rollers considerable idling of the gears took place which caused backlash, especially at high speeds.

Among the objects of this invention are the making of a machine of this type which may be made much lighter and less expensive than the former machines and which will operate at this increased speed without placing undue strain upon any of the parts of the machine. Another object of the invention is to eliminate a number of these intermediate gears so that at the increased speed there may be less backlash and free play of the various rollers. Other objects and advantages of the new construction will be apparent from the following description and the accompanying drawings forming a part hereof and in which:

Figure 1 is a side elevation of the feeding end of the machine.

Figure 2 is a similar view of the delivery end of the machine.

Figure 3 is a transverse sectional view of the intermediate pull rollers showing the eccentric adjustment of the lower pull roller.

Figure 4 is a sectional view on line 4, 4 of Figure 3.

Figure 5 is a plan view of the adjustment shaft with the locking means therefor.

In the drawings similar reference characters refer to similar parts throughout the several views. The side frames 1, 2 are mounted on base 3 and the sections of said frames at the delivery end of the machine are rigidly attached to this base, as shown in Figure 2. The feeding end sections of these frames as shown in Figure 1 are slideable on this base through means of racks and pinions 4, 5, the latter being turned by handle 6 and the shaft of pinions 5 passing across the machine. The racks 4 are rigidly fixed on the feeding sections of the machine. The sections are locked together by means of locking mechanisms 7 duplicated on both sides of the machine and operated by lever 8. The sections may thus be separated so that the operator can readily have access to the printing rollers to adjust the type plates thereon.

The printer slotter shown has initial pull rollers 9, 10, printing cylinders 11 and 12, with intermediate pull rollers therebetween 13, 14, and back

of printing roller 12 is scoring roller 15, and this is then followed by slotting roller 16. After the boards have been delivered from the machine they pass to conveyors 17 from which they are 5 removed by the operator in their completed condition.

The boards are fed to the initial pull rollers 9 and 10 from stack 18. This stack is pushed against an adjustable upright or gauge 19 which 10 allows only the lower sheet of board to pass beneath the same. The stack of boards is held in position at its other end by upright 20 which may be adjusted lengthwise of the bed holding the stack and is held fast thereto by bolt 21. This 15 upright 20 is composed of several sections placed horizontally across the bed and has projecting therefrom supports 22 on which the rear end of the stack rests. Between these uprights 20 pass spring held reciprocating feed fingers 23 having 20 thereon pull sections 24 which, when the fingers have passed back of the sheet, spring up and in their next reciprocation pull off the bottom sheet and feed the same to the initial pull rollers. These fingers 23 are fast on a horizontal bar 25 25 rigidly attached to member 26 which is reciprocated by lever 27.

The initial printing cylinder 11 is shown as having inking mechanism generally indicated at 28 and the next printing cylinder 12 as having 30 inking mechanism generally shown at 29. Type plates 30 are shown on cylinder 11 and 31 on cylinder 12. The slotting cylinder is shown as having knives 32 thereon.

The rollers are driven from a motor 33 operating 35 a Reeves drive 34 which has thereon a gear 35, driving gear 36, and the shaft of gear 36 has thereon another gear 37 driving gear 38 which, in turn, drives gear 39, and gear 39 drives gear 40 on the shaft of the first printing cylinder 41. The reciprocating lever 27 is reciprocated by 40 means of being connected to a pin. The reciprocating lever 27 is reciprocated by means of being connected by a pin to rocking lever 41, keyed to the center of rocking shaft 42. Rocking shaft 45 45 42 obtains its rocking motion from the frame 43 keyed thereto and in which reciprocates a sliding block 44 carrying a ball bearing, the axis of which forms a pin on one side of gear 38, whereby the rotation of gear 38 moves the sliding block 44 50 up and down in the frame 43 and rocks the same back and forth.

Gear 37 on the shaft of lower pull roller 10, the shaft of which is mounted on bearings fixed in the side frames 1, 2 of the machine, drives a gear 55 55 on the shaft of upper pull roller 9 to rotate the same. Upper pull roller 9 is pivotally mounted on swinging arms 56 pivoted to the side frames of the machine. This upper pull roller 9 is resiliently held in its adjusted position by means of 60 shaft 57 passing through the ends 58 of arms 56 and it is held down by spring 59. This structure is old in the art and is therefore shown only diagrammatically. It will be apparent that the side frames are solid and therefore not weakened 65 vertically between these upper and lower initial pull rollers 9 and 10. The side frames are also solid vertically between the upper and lower intermediate pull rollers 13 and 14 so that the side frames are not weakened vertically by either the 70 pull roller adjustments or the adjustments on the printing and slotter presser rollers. From gear 40 on the shaft of printing cylinder 11, gear 41 transmits power to the inking rollers 29.

Gear 40 likewise transmits power to interme-

diate gear 42 which transmits the power on to gear 43 on the shaft of printing cylinder 12. From this gear 43 power is transferred to another intermediate gear 44 which drives the inking mechanism 29 and also the gear 45 on the 5 shaft of the scoring roller 15, and the gear 46 on the shaft of the slotter roller 16.

The impression cylinder 47 for printing cylinder 11 has on its shaft, gear 48 which is driven from gear 40. The shaft 49 of this impression 10 cylinder, herein sometimes referred to as a presser roller, is now mounted in an eccentric bearing so that the cylinder may be adjusted toward or from the shaft of impression cylinder 11. The adjustment of this shaft is identical to 15 that of shaft 50 for the intermediate pull roller 14, and will be described in detail in relation thereto. The adjustment of impression cylinder 51 for printing cylinder 12 is of the same type as is also that of the lower roller 52 for the scoring roller 15 on its shaft 53. The adjustment of shaft 54 carrying the lower roller 55 for the slotting roller 16 is of the same type. All of these lower rollers, eccentrically adjustable as stated, are herein sometimes referred to as lower presser 20 25 rollers because they all maintain the work up against the upper roller which either forwards or operates upon the board passing therethrough.

Gear 42 likewise drives gear 56 on shaft 57 of intermediate pull roller 13. Pull roller 13 is 30 mounted in bearings with a lubricating means provided therefor, as shown in Figure 3. The roller has various pull members 58 thereon to pull the sheets through from the first printing cylinder to the second. The shaft 50 of lower 35 pull roller 14 is mounted at each end in eccentric sleeve bearings with gears 59 on the outer ends thereof. Ball bearings 60 in these sleeve bearings allow complete rotary motion to the shaft 50 in these eccentric sleeves. Gear 61 keyed 40 to shaft 50 and intermeshing with gear 56 rotates shaft 50 so that rollers 13 and 14 rotate in unison. The gears of sleeve bearings 59 may be rotated by gears 62 meshing therewith, and gears 63 are mounted on a shaft 64 extending through 45 the machine, and the same may be turned from the square head 65 projecting from one side of the machine. The eccentric sleeve bearings are so placed in the side frames of the machine that 50 rollers 13 and 14 are parallel and so that in any rotary position of the eccentric sleeve bearings they will remain parallel, but this rotating of the eccentric sleeve bearings will move the rollers 13 and 14 either nearer together or further apart 55 so that different thicknesses of material may pass between the same.

After proper adjustment of the eccentric sleeve bearing to give the desired distance between the presser roller and the corresponding upper operating roller, it is desirable to lock the shaft 63 in 60 its adjusted position, and this is done in the manner following: A plate 66 having a split collar 66 integral therewith for half the diameter of the collar 66, is bolted to the side frame 1 of the machine so that the collar 66 surrounds the shaft 63. 65 The split collar 66 has upwardly projecting ears 67 thereon, and through these ears 67 a bolt 68 is passed, the same being threaded to one ear 67, and the hole in the other ear being enlarged to permit free passage of the bolt therethrough. 70 This bolt may be rotated for drawing the ears together by lever 69 having set screw 70 holding the same tightly on the bolt 68.

The eccentric bearing adjusting rods are identical in each case for the shafts 49, 50, 51, 53 and 75

54, and the square heads to turn the same have all been identified by numeral 64. Adjustment of the various eccentric bearings will allow varying thicknesses of board to be run through the 5 machine. Since the lower presser roller in each case is driven directly from gears on the shafts of the upper operating rollers, the teeth on these contacting gears might be a trifle longer than usual and the adjustments between the presser 10 rollers and their operating rollers must not be so great as to throw these teeth out of mesh. Accurate timing is required between the various printing cylinders and the slotting roller and between the gears driving these operating rollers 15 no adjustment is required and therefore the accurate timing may be maintained. Accurate timing of the lower rollers which rotate bodily in a circle during their eccentric adjustments is not required and therefore these eccentric 20 adjustments do not throw off the timing of the machine. Since only one roller in each case is driven after being adjusted from each accurately timed driving roller and the only free play involved in running the complete machine is in 25 these presser rollers and it has been found in practice that much less free play occurs in driving this machine at the high speed for which it is designed with the lower rollers being directly driven through gears from the upper rollers than 30 was involved when the various intermediates were employed in driving the lower rollers from the upper rollers. Since the side frames do not have to be cut away to allow for the vertical adjustment of the lower presser rollers the side frames 35 will be much stronger between the rollers longitudinally of the machine than has been possible where the vertically adjusted lower rollers have been used for the same strength, previously obtained by heavy side frames, much lighter side 40 frames and less expensive frames may now be used. Also, the omission of the intermediate gears which are required by the vertical adjustment of the presser rollers, saves considerable in the expense of the production of the machine, 45 these machines being subjected to a heavy intermittent load passing longitudinally through the machine and vertically between the rollers, subjecting the machine to very considerable stress when operated at the high speeds for which they 50 are designed, and this eccentric mounting of the presser rollers absorbs this stress in a much lighter structure than has been possible with the more common vertically adjustable presser roller.

What is claimed as new and is desired to secure 55 by Letters Patent is:

1. A printer-slotter for sheet material comprising printing and slotting rollers, a presser roller parallel to and beneath each of said rollers to hold material thereagainst, all said rollers being mounted on shafts having gears thereon, means to drive said printing and slotting rollers independently of the drive of said presser rollers, each presser roller being driven directly by said gears from its respective upper roller, the shafts of said presser rollers being mounted at each end in eccentrically movable bearings, and means to rotate both bearings of each shaft simultaneously, whereby each presser roller shaft may be bodily moved in a circle and always maintained parallel to its respective upper roller shaft and the distance between said presser rollers and their respective upper rollers may be varied to accommodate different thicknesses of material therebetween.

2. A printer-slotter for sheet material comprising

ing printing and slotting upper rollers, a presser roller parallel to and beneath each of said rollers to hold material thereagainst, all said rollers being mounted on shafts, means to drive all of said rollers, the printing and slotting rollers being driven independently of the presser rollers, and each presser roller being driven from its respective upper roller the shafts of said presser rollers being mounted at each end in eccentrically movable bearings, and means to rotate both bearings 5 of each shaft simultaneously, whereby each presser roller shaft may be bodily moved in a circle and always maintained parallel to its respective upper roller shaft, and the distance between said presser rollers and the respective upper rollers may be 10 varied to accommodate different thicknesses of material therebetween, reciprocating means to successively feed sheets of material between said upper and lower rollers.

3. A printer-slotter for sheet material comprising upper printing and slotting rollers, a presser roller parallel to and beneath each of said rollers to hold material thereagainst, all of said rollers being mounted on shafts, means to drive said rollers, the printing and slotting rollers being driven 20 independently of the presser rollers, and each presser roller being driven from its respective upper roller the shafts of said presser rollers being mounted at each end in eccentrically movable bearings and means to rotate both bearings of 25 each shaft simultaneously whereby each presser roller shaft may be bodily moved in a circle and always maintained parallel to its respective upper roller and the distance between said presser rollers and their respective upper rollers may be 30 varied to accommodate different thicknesses of material therebetween, means to successively feed sheets of material between said upper and lower rollers, vertical longitudinally extending side 35 frames supporting the shafts and bearings of said 40 rollers, said frames being longitudinally solid between the respective upper and lower rollers along the line of the passage of the material therebetween.

4. A printer slotter for sheet material comprising printing and slotting rollers, a presser roller parallel to and beneath each of said rollers to hold the material thereagainst, all said rollers being mounted on shafts having gears thereon, means to drive said printing and slotting rollers 45 independently of the drive of said presser rollers, each presser roller being driven directly by said gears from its respective upper roller, the shafts of said presser rollers being mounted at each end in eccentrically movable bearings, and means 50 to rotate both bearings of each shaft simultaneously, whereby each presser roller shaft may be bodily moved in a circle and always maintained parallel to its respective upper roller shaft and the distance between said presser rollers and their 55 respective upper rollers may be varied to accommodate different thicknesses of material therebetween and reciprocating means to successively feed sheets of material between said upper and lower rollers.

5. A printer-slotter for sheet material comprising printing and slotting rollers, a presser roller parallel to and beneath each of said rollers to hold material thereagainst, all said rollers being mounted on shafts having gears thereon, means 60 to drive said printing and slotting rollers independently of the drive of said presser rollers, each presser roller being driven through said gears by its respective upper roller, the shafts of 65 said presser rollers being mounted at each end 70 75

in eccentrically movable bearings, and means to rotate both bearings of each shaft simultaneously, whereby each presser roller shaft may be bodily moved in a circle and always maintained parallel to its respective upper roller shaft and the distance between said presser rollers and their respective upper rollers may be varied to accommodate different thicknesses of material therebetween, means to successively feed sheets of material between said upper and lower rollers, vertical longitudinally extending side frames supporting the shafts and bearings of said rollers, said frames being longitudinally solid between the respective upper and lower rollers along the line of the passage of material therebetween.

6. A printer-slotted for sheet material comprising printing and slotting upper rollers, a presser roller parallel to and beneath each of said rollers to hold material thereagainst, all said rollers being mounted on shafts, means to drive all of said rollers, the shafts of said presser rollers being mounted at each end in eccentrically movable bearings, and means to rotate both bearings of each shaft simultaneously, whereby each presser roller shaft may be bodily moved in a circle and always maintained parallel to its respective upper roller shaft, and the distance between said presser rollers and the respective upper rollers may be varied to accommodate different thicknesses of material therebetween, reciprocating means to successively feed sheets of material between said upper and lower rollers, vertical longitudinally extending side frames supporting the shafts and bearings of said rollers, said frames being longitudinally solid between the respective upper and lower rollers along the line of the passage of the material therebetween.

7. A printer-slotted for sheet material comprising printing and slotting rollers, a presser roller parallel to and beneath each of said rollers to hold material thereagainst, all said rollers being mounted on shafts having gears thereon, means to drive said printing and slotting rollers independently of the drive of said presser rollers, each presser roller being driven through said gears by its respective upper roller, the shafts of said presser rollers being mounted at each end in eccentrically movable bearings, and means to rotate said bearings whereby each presser roller shaft may be bodily moved in a circle and the distance between said presser rollers and their respective upper rollers may be varied to accommodate different thicknesses of material therebetween, and means to lock said bearings in their adjusted positions.

8. A printer-slotted for sheet material comprising printing and slotting rollers, means to drive said rollers, a presser roller parallel to and beneath each of said rollers to hold material thereagainst, all said rollers being mounted on shafts having gears thereon, each presser roller being driven through said gears by its respective upper roller, the shafts of said presser rollers being mounted at each end in eccentrically movable bearings, and means to rotate said bearings whereby each presser roller shaft may be bodily moved in a circle and the distance between said presser rollers and their respective upper rollers may be varied to accommodate different thicknesses of material therebetween and means to lock said bearings in their adjusted positions, vertical longitudinally extending side frames supporting the shafts and bearings of said rollers, said frames being longitudinally solid between

the respective upper and lower rollers along the line of the passage of material therebetween.

9. A printer-slotted for sheet material comprising printing and slotting rollers, means to drive said rollers, a presser roller parallel to and beneath each of said rollers to hold material thereagainst, all said rollers being mounted on shafts having gears thereon, each presser roller being driven through said gears by its respective upper roller, the shafts of said presser rollers being mounted at each end in eccentrically movable bearings, and means to rotate said bearings whereby each presser roller shaft may be bodily moved in a circle and the distance between said presser rollers and their respective upper rollers may be varied to accommodate different thicknesses of material therebetween and means to lock said bearings in their adjusted positions, vertical longitudinally extending side frames supporting the shafts and bearings of said rollers, said frames being longitudinally solid between the respective upper and lower rollers along the line of the passage of material therebetween, said side frames being vertically divided adjacent said printing roller to allow access to said printing roller, means to separate said divided sections and means to lock the same together.

10. A printer-slotted for sheet material comprising printing and slotting rollers, means to drive said rollers, a presser roller parallel to and beneath each of said rollers to hold material thereagainst, all said rollers being mounted on shafts having gears thereon, each presser roller being driven through said gears by its respective upper roller, the shafts of said presser rollers being mounted at each end in eccentrically movable bearings, and means to rotate both bearings of each shaft simultaneously, whereby each presser roller shaft may be bodily moved in a circle and always maintained parallel to its respective upper roller shaft and the distance between said presser rollers and their respective upper rollers may be varied to accommodate different thicknesses of material therebetween, means to successively feed sheets of material between said upper and lower rollers, vertical longitudinally extending side frames supporting the shafts and bearings of said rollers, said frames being longitudinally solid between the respective upper and lower rollers along the line of the passage of material therebetween, said side frames being vertically divided adjacent said printing roller to allow access to said printing roller, means to separate said divided sections and means to lock the same together.

11. A printer slotter for sheet material comprising upper printing and slotting rollers, a presser roller parallel to and beneath each of said rollers to hold material thereagainst, all of said rollers being mounted on shafts, means to drive said rollers, the printing and slotting rollers being driven independently of the presser rollers, and each presser roller being driven from its respective upper roller, the shafts of said presser rollers being mounted at each end in eccentrically movable bearings, and means to rotate said bearings, whereby each presser roller shaft may be bodily moved in a circle, and the distance between said presser rollers and their respective upper rollers may be varied to accommodate different thicknesses of material therebetween, reciprocating means to successively feed sheets of material between said upper and lower rollers.

THOMAS S. FITCHETT.
